UNITED STATES PATENT OFFICE

FELIX J. TRAINOR, OF NEW CASTLE, INDIANA, ASSIGNOR TO TRAINOR NATIONAL SPRING COMPANY, OF NEW CASTLE, INDIANA, A CORPORATION

RESILIENT STRUCTURE FOR CHAIRS AND THE LIKE

Application filed July 5, 1932. Serial No. 620,819.

This invention relates to the art of furniture and particularly to a chair or the like having a flexible, elastic frame. It is a primary object of my invention to construct a 5 chair or bench to give an action approaching that of the ordinary rocking chair but which will not have curved rockers. A primary object of the invention also is to provide a chair of the above indicated nature in which the 10 base or floor contacting members are straight and initially in full contact with the floor.

A still further important object of the invention is to provide a structure in which the person sitting thereon may cause the structure to conform to his desired sitting position by merely leaning back or may rock to and fro as desired all without any tendency of the structure to tend to tip over backwardly or to pitch the person forward. A still further 20 important object of the invention is to provide a resilient frame to secure comfort not heretofore available and to do so with the maximum safety as well as cheapness in cost of production.

These and other objects and advantages will become apparent to those versed in the art by the following description of one particular form of the invention as illustrated by the accompanying drawing, in which

Fig. 1 is a side elevation of a structure embodying my invention,

Fig. 2, a front elevation, and

Fig. 3, a fragmentary top plan view.

Like characters of reference indicate like parts throughout the several views in the drawing.

I form a pair of flat somewhat elongated runners 10 and 11 out of spring steel stock, the thickness for one particular size of chair being three-sixteenths of an inch. These runners are made to be straight so as to be in contact throughout substantially their entire length with the floor. For the purpose of finish or appearance, the rear ends may be formed to have eyes 12 although the runners may be left plain as desired. The forward end of each runner is curved slightly upwardly and fixed thereto respectively are the lower ends of the legs 13 and 14. These legs are made out of flat bar spring steel stock,

preferably somewhat lighter than that of the runners and have S curves 15 formed therein immediately above their connections with the runners.

The upper ends of the legs 13 and 14 are 55 curved around rearwardly and arched downwardly somewhat to form side rails across which the seat slats 16 are placed and secured thereto. U-shaped spring members 17 and 18 are placed respectively between these 60 side rails and the runners 10 and 11 thereunder to have their open ends turned forwardly and secured rigidly to the rails and runners. The points of attaching these ends to the seat rails and runners determine to 65 quite an extent the action to be obtained from the completed chair. A very satisfactory chair is produced by locating the spring members as indicated in Fig. 1 where the top end of the spring member is secured to 70 the rail at substantially one-half way between the rear end of the rail and the downturned leg in front. Normally the legs 13 and 14 without load are vertically disposed and the spring members 17 and 18 contact 75 with the runners directly below the points of contact with the seat rails above. While the lower ends of these spring members thus contact the runners, these lower ends are secured to the runners somewhat ahead of 80 their initial contact therewith. Preferably the runners are spaced horizontally further apart than are the seat rails and a tie 19 is employed to have its ends resting on the top sides of the lower ends of the spring members 85 17 and 18 to be rigidly united thereto so as to rigidly space apart the two runners. A back is formed to have a flat band 20 of spring steel secured to the rear ends of the seat side rails to extend upwardly and backwardly somewhat to curve around with a form fitting horizontal portion between which portion and the back slat of the seat is placed a panel 21.

Arm rests 22 and 23 are mounted on bands 95 of spring steel 24 and 25 which are pressed edgewise against the under sides of the rests to have their rear ends carried around and secured to the back sides of the downturned portions of the band 20 while the forward 100 ends curve downwardly and thence inward-

ly to be secured against the under sides of the respective seat rails. Angle brackets 26 are secured to these bands 24 and 25 as a means of contacting the rests thereto.

5 The action of the chair in use is indicated somewhat by the dash lines in Fig. 1 where-
in it is shown that under load the spring
members 17 and 18 will be compressed some-
what to allow the side rails of the seat to
10 bend downwardly about the upper ends of
the legs 13 and 14 and if the person in the
seat leans backwardly, the spring members
17 and 18 will tend to roll back into further
15 contact with the runners 10 and 11 while the
forward ends of the runners bend upwardly
away from the floor, the rear ends of the run-
ners always remain in contact with the floor
in a straight line position. The S curves 15
while largely provided for the sake of ap-
20pearance afford some additional resiliency
between the runners and the legs. Also the
rear part of the seat may spring downwardly
to have the rails come into further con-
tact with the springs 17 and 18 since the rear
25 part of the seat is in reality supported in a
cantilever manner. Since the arm rest sup-
port bands 24 and 25 are connected to the
back and to the side rails near their forward
ends, backward movement of the back will
30 tend to pull up on the forward ends of the
seat rails and thus tend to lift the front ends
of the runners 10 and 11. Since the side
rails of the seat, the spring members 17 and
18 and the runners 10 and 11 are each and
35 all made out of spring steel, the members
will return to their initial normal positions
as indicated by the solid lines upon the
weight being removed from the chair. Since
the runners 10 and 11 are always in contact
40 with the floor throughout the major parts of
their lengths, there is no tendency of the
chair to crawl or travel over the floor al-
though the seat may be rocked vigorously.

While I have attempted to describe the
45 operation of the individual members of the
chair, the action of each member is in fact
limited by the action of the adjacent at-
tached member so that each and all of the
members cooperate one with the other to give
50 a total resilient and elastic action. The vari-
ous members are made out of relatively thin
steel so that the total combined weight of the
chair or unit does not exceed that of the
usual chair of other construction of substan-
55 tially the same size. While it would be pos-
sible to make the legs 13 and 14 integral with
the runners 10 and 11, I have here shown
them as separate members for the reason
60 that I find it entirely practical to make the
legs and seat rails out of lighter stock than
is employed in the runners 10 and 11.

While I have herein shown and described
my invention in more or less minute detail
it is entirely obvious that structural changes
65 may be made such as in the back, arm rests

and seat construction which may be uphol-
stered if desired, all without departing from
the spirit of the invention, and I therefore
do not desire to be limited to that precise
form except as may be required by limita-
tions imposed by the following claims. 73

I claim:

1. In an article of furniture, a pair of
elastic runners normally substantially hori-
zontal contacting with the floor, a pair of 75
substantially normally vertical legs secured
respectively by their lower ends to the for-
ward ends of the runners, seat rails running
rearwardly from the legs, and a U-shaped
elastic member between and secured by its 80
ends to the respective runners and seat rails
on each side.

2. In an article of furniture, a pair of
elastic runners normally substantially hori-
zontal contacting with the floor, a pair of 85
substantially normally vertical legs secured
respectively by their lower ends to the for-
ward ends of the runners, seat rails running
rearwardly from the legs, and a U-shaped
elastic member between and secured by its 90
ends to the respective runners and seat rails
on each side, and a cross tie between the run-
ners at the ends of said elastic members.

3. In an article of furniture, a pair of
elastic runners normally substantially hori-
zontal contacting with the floor, a pair of 95
substantially normally vertical legs secured
respectively by their lower ends to the for-
ward ends of the runners, seat rails running
rearwardly from the legs, and a U-shaped
elastic member between and secured by its 100
ends to the respective runners and seat rails
on each side, said U-shaped members being
turned to have their ends directed forward-
ly whereby compression of the members will 105
tend to bring a greater portion thereof into
contact with the runners back of the con-
necting points therewith.

4. In an article of furniture, a pair of
parallel arranged elastic runners normally 110
substantially horizontal contacting with the
floor, an elastic leg substantially normally
vertical secured to each of the runners at
their forward ends, elastic seat rails running
rearwardly from the legs, and an elastic U-
115 shaped member between each rail and the
runner thereunder, the ends of the members
being secured to the rails and runners for-
wardly of the rear ends thereof.

5. In an article of furniture, a pair of
parallel arranged elastic runners normally
substantially horizontal contacting with the
floor, an elastic leg substantially normally
vertical secured to each of the runners at
120 their forward ends, elastic seat rails running
rearwardly from the legs, and an elastic U-
shaped member between each rail and the
runner thereunder, the ends of the members
being secured to the rails and runners for-
wardly of the rear ends thereof, a back se- 125
130

cured to the seat rails, and arm rest supports interconnecting the back and the seat rails, the forward ends of the supports being secured to the rails ahead of the ends of said members.

6. In an article of furniture, a pair of normally straight horizontal elastic runners contacting the floor, a seat above the runners, front legs substantially normally vertical
10 fixed between the seat and the runners and curved rear seat support members fixed between the seat and the runners, said runners being yieldingly pulled upwardly by their front ends to wrap against the said members
15 upon the rearward tilting of the seat.

7. In an article of furniture, a pair of normally straight horizontal elastic runners contacting the floor, a seat above the runners, front legs substantially normally vertical
20 fixed between the seat and the runners and curved rear seat support members fixed between the seat and the runners, said runners being yieldingly pulled upwardly by their front ends to wrap against the said members
25 upon the rearward tilting of the seat, said seat rails being elastic and tending to bend downwardly against said members under load to be reinforced thereby.

8. In an article of furniture, a pair of normally straight horizontal elastic runners contacting the floor, a seat above the runners, front legs substantially normally vertical
30 fixed between the seat and the runners and curved rear seat support members fixed between the seat and the runners, said runners being yieldingly pulled upwardly by their front ends to wrap against the said members
35 upon the rearward tilting of the seat, said seat rails being elastic and tending to bend downwardly against said members under load to be reinforced thereby, said members being elastic and essentially U-shaped with their ends forwardly directed.

In testimony whereof I affix my signature.
45 FELIX J. TRAINOR.
